H. C. RIDLER

COOLING DEVICE FOR DRINKING FOUNTAINS

Filed August 20, 1925

Patented June 8, 1926.

1,588,055

UNITED STATES PATENT OFFICE.

HARRY C. RIDLER, OF MINNEAPOLIS, MINNESOTA.

COOLING DEVICE FOR DRINKING FOUNTAINS.

Application filed August 20, 1925. Serial No. 51,835.

My present invention is in the nature of a modification of or improvement on the cooling device for drinking fountains disclosed and broadly claimed in my prior Patent No. 1,539,867, of date June 2, 1925, and, generally stated, the invention consists of the novel construction, combinations and arrangement of parts hereinafter described ad defined in the claims.

10 Particularly, this invention relates to water-cooling systems of the character above described, wherein the system is arranged to supply cold water to drinking fountains located on different floors of a building. In 15 such a system, the drinking water is cooled by passing the same through a refrigerator and the waste from the fountains is utilized to assist in the cooling action. When 20 all of the fountains are frequently used, the water will be kept cold or in cooled condition, but when one of the drinking fountains, say one located on one of the upper 25 floors, is infrequently used, the circulation will not be kept up and the relatively warm water will accumulate in the water supply pipe to such upper fountain, and the drinking water supplied thereto will become objectionably warm.

30 My present invention provides an automatic device whereby, when the water in the pipes of the upper or infrequently used fountain is raised above a predetermined temperature, a leakage or regulated escape of the warm water will be permitted and when the water is then being cooled to a predetermined condition, further leakage or escape of water will be automatically cut off.

35 The invention is illustrated in the accompanying drawings, wherein like characters indicate like parts throughout the several views.

Referring to the drawings:

40 Fig. 1 is a view partly in elevation and partly in vertical section, showing the system, with the invention incorporated, applied to several fountains located on different floors of a building, fragments of the latter only being shown;

45 Fig. 2 is an enlarged view partly in side elevation and partly in vertical section and with some parts broken away, showing the upper portion of the water-conducting system;

50 Figs. 3 and 4 are plan views showing

washers used in connection with the automatic valve-regulating means; and

Fig. 5 is a fragmentary view partly in section and partly in elevation, illustrating a modified arrangement of the water-distributing system and the upper drinking fountain of the system.

Describing first the preferred construction shown in Figs. 1 to 4, inclusive, the numeral 6 indicates as an entirety the refrigerator, which may be and preferably is of the type disclosed in my said prior patent and the same being, as shown, located in the basement of the building, which latter is indicated as an entirety by the character 65 A. The drinking fountains located on the several floors are indicated as entireties by the character B. The numeral 7 indicates a vertical waste water pipe or stack, which may be located in the wall of the building and the lower end of which delivers the cold waste water back into the refrigerator 6 for cooling purposes, all as fully described in my prior patent. Each fountain B is connected by a waste water pipe 8 to the 70 waste water stack 7, preferably by T-couplings 9.

The cold water supply pipe 10 will be connected to a source of water supply under 75 pressure and is extended through the refrigerator 6, and in the preferred arrangement illustrated, is passed upward through the drain stack 7. The several drinking fountains B receive the cold water through 80 branch pipes 11 that are extended through the branch waste pipes 8 and are connected to the vertical portion of the cold water supply pipe 10 by T-couplings 12. The 85 connections now described will deliver cold water from the refrigerator to the fountains on the several floors and will carry the cold waste water from the several fountains back to the refrigerating chambers of the refrigerator; but a system involving 90 only the connections so far noted would be subject to the objectionable feature above noted as to the accumulation of relatively warm water at upper or infrequently used fountains.

95 A preferred form of the automatic regulator will now be described:

The uppermost section 10^a of the water supply pipe 10 is made of brass or other metal that has a greater coefficient of expansion than steel or iron; and in the 100 110

structure shown, the lower end of this brass section 10^a, by means of a coupling sleeve 13, is connected to a tubular nipple 14, which, in turn, is screwed into the immediately underlying T-coupling 12. A perforated washer 15 shown in detail in Fig. 3 is placed in the coupling sleeve 13 and clamped between the lower end of the brass tube 10^a and the upper end of the nipple 14. A valve rod 16, which is of much less diameter than the interior of the brass tube 10^a, is rested at its lower end on the washer 15 and its upper end is extended through and above the uppermost T-coupling 12 and is terminated in a conical end or needle valve 17. A tube or pipe section 18 is screwed into the top of the uppermost T-coupling 12 and loosely surrounds the upper end of the valve rod 16. Attached to the upper end of the tube 18, preferably by threaded engagement, is a valve casing 19, and by said threads is made vertically adjustable. The valve casing 19 immediately overlying the needle valve 17 is shown as provided with an axially located depending bushing 20 that affords a valve seat for said needle valve. On the top of the valve casing 19 and communicating therewith is a secondary valve casing 21, shown as provided with an inlet port 22 and with a discharge port 23. The inlet port 22 is adapted to be opened and closed more or less by a needle valve 24 that has threaded engagement with the upper end of said secondary valve casing 21. To enclose the valve structure just described, a large tube or pipe section 25 is screwed into the top of the uppermost T-coupling 9 and, as shown, is provided with a detachable cap 26.

All of the pipes and tubes above described and the valve rod 16 may be of iron or steel and, hence, have a lower coefficient of expansion than the brass expansion tube or pipe section 10^a. By adjustments of the valve casing 19 on the upper end of the tube 18, the tubular valve seat 20 can be adjusted in any position in respect to the needle valve end 17 of the valve rod. The adjustment should be such that the needle valve 17 will close the valve seat 20 when the temperature of the water in the tubes 10^a and 18 is at the desired low temperature for drinking. When, however, the water in these tubes is of a higher temperature than that just noted, the brass tube 10^a will expand more rapidly than the valve rod 16 and will cause the needle valve 17 to open the valve seat 20 and permit the escape of water through the secondary valve casing 21 and its discharge port 23. This will cause the warm water to be displaced and the relatively colder water to fill the tubes 10^a and 18, and this water at a lower temperature will cause the tube 10^a to contract more rapidly than does the valve rod 16,

thereby causing the needle valve 17 to close the valve seat 20 and stop the discharge of water. By this automatic valve device, cold water is always kept in the upper portion of the drinking water supply tube and, hence, available for drinking at all of the fountains. For guiding the needle valve 17 at the upper end of the valve rod 16, a perforated spacing washer 27 is placed at the upper end of the tube 18, through which the expansion rod freely moves.

In the modified construction illustrated in Fig. 5, the automatic valve mechanism and the cold water supply pipe are located outside of the waste water pipes 7 and 8. In this arrangement, a cold water supply pipe 10^b is connected to the fountain B by a branch pipe 11^b; the brass pipe section 10^c is connected between the pipe 10^b and the valve casing 19; and the discharge port 23 of the secondary valve casing 21 is connected to the upper end of the waste pipe 7 by a short pipe 23^a.

By adjustments of the valve 24, the extent of the flow or escape of water from the escape passage afforded by the valve seat 20, casing 21 and port 23 may be regulated.

What I claim is:

1. The combination with a refrigerator and a drinking fountain, of a drinking water supply pipe extended from said refrigerator to said fountain, said supply pipe having an escape passage, and a thermally actuated valve operative to open said escape passage when the drinking water in said supply pipe is above a predetermined temperature and to close said escape passage when the water is at a predetermined lower temperature.

2. The combination with a refrigerator and a drinking fountain, of a drinking water supply pipe extended from said refrigerator to said fountain, said supply pipe having an escape passage, a thermally actuated valve operative to open said escape passage when the drinking water in said supply pipe is above a predetermined temperature and to close said escape passage when the water is at a predetermined lower temperature, and means independent of said thermally actuated valve for regulating the extent of discharge when the said escape passage is open.

3. The combination with a refrigerator and a drinking fountain, of a drinking water supply pipe connecting said refrigerator to said fountain, a valve casing applied to the upper portion of said supply pipe and having an escape passage therein, and a valve rod seated in said supply pipe with its upper end operating as a valve to open and close said escape passage, under expansion and contraction of said supply pipe.

4. The combination with a refrigerator and a drinking fountain, of a drinking wa-

ter supply pipe connecting said refrigerator to said fountain, a valve casing applied to the upper portion of said supply pipe and having an escape passage therein, and a valve rod seated in said supply pipe with its upper end operating as a valve to open and close said escape passage, said expansion rod and the surrounding portion of said supply pipe being of different metals and having different coefficients of expansion, the coefficient of expansion of said pipe being greater than that of said rod.

5. The structure defined in claim 3 in which said escape passage is provided with an adjustable valve for regulating the rate of discharge of water when said escape passage is opened.

6. The structure defined in claim 4 in further combination with a secondary valve casing applied to and receiving from the first noted valve casing and having a discharge port, and a needle valve applied to said secondary valve casing for regulating the rate of discharge of water therethrough.

25 7. The combination with a refrigerator and a plurality of drinking fountains located at different elevations, of a drinking water supply pipe comprising a stack con-

nected to the several drinking fountains by branch supply pipes, a waste pipe freely enclosing the stack of said water supply pipe and having branch waste pipes enclosing the branch water supply pipes and connected to the respective fountains, a valve casing applied to the upper end of the stack of said water supply pipe and having an escape passage, and a valve rod seated in the upper portion of the stack of said water supply pipe with its upper end arranged to act as a valve to open and close the escape passage of said valve casing, the upper portion of said stack being of a metal that has a greater coefficient of expansion than said valve rod, whereby the said escape passage will be closed when the drinking water is at a predetermined low temperature and will be opened when the drinking water is at higher temperature.

8. The structure defined in claim 7 in further combination with a valve for regulating the flow of the water through said valve casing when said escape passage is opened.

In testimony whereof I affix my signature.

HARRY C. RIDLER.
